UNITED STATES PATENT OFFICE.

THADDEUS S. SMITH, OF ST. LOUIS, MISSOURI.

BRICK-KILN.

SPECIFICATION forming part of Letters Patent No. 290,939, dated December 25, 1883.

Application filed February 27, 1883. (No model.)

To all whom it may concern:

Be it known that I, THADDEUS S. SMITH, a citizen of the United States, and a resident of the city of St. Louis, in the State of Missouri, have invented certain new and useful Improvements in Brick-Kilns; and I do hereby declare the following to be a full, clear, and exact description of the same, reference being had to the accompanying drawings, forming part of this specification.

My invention relates more especially to improvements in that class of kilns known as the "Scotch" or "open-topped" kiln, and has for its objects, first, to provide means for drying or removing the free moisture from green bricks after they are set in the kiln, and, second, to furnish a means for burning the top courses of brick in the kiln into good hard brick. I attain these objects by the construction and arrangement of parts illustrated in the accompanying drawings, in which—

Figure 1 is a perspective view; Fig. 2, a transverse section, and Fig. 3 a longitudinal section.

The first part of my improvement consists in an improved mode of drying off the green bricks after they are set or stacked up in the kiln for the purpose of being burned. This I accomplish in a very perfect and economical manner by the introduction of a coil or coils of pipe, A, within the usual arches, B, that are left in the setting of the bricks in the kiln C. These coil or coils of pipe may be of any suitable form, and are so connected that a current of steam will circulate through them, in order to heat the air within the arches, B. Such heated air, in passing upward through the interstices in the mass of green bricks, acts by its absorbent power to gradually deprive the bricks of their moisture, and at the same time raise their temperature to a point where any fuel can be directly used.

My improved mode of drying the green bricks also possesses great economy and efficiency over the usual method heretofore employed, there being no vaporous gas produced, (as in the burning of wood,) to be condensed into a sweat by the mass of bricks while yet cold, and no ashes or soot deposited to choke up the interstices between the bricks.

I prefer to mount the steam-coils A upon

trucks or wheels a, so that when the preliminary or drying operation is completed such coils can be readily withdrawn from the kiln-arches, after which regular fires can be established within the arches, and the process of burning the bricks to a red and white heat successively, as usual, be proceeded with.

The pipe-connections, controlling-valves, &c., between the coils A and the steam-boiler 60 supplying steam to the coils will be of any of the usual constructions known to the art.

To promote the draft through the mass of bricks, flues or passages d, transverse to the arches B, are formed at the top of the kiln, 65 either under the flatting or covering D' of the kiln or within or above the said flatting, and may be formed of brick or any other suitable material. These transverse flues d lead or open into a main flue, D, at right angles to 70 such transverse flues, and are in communication with a smoke-stack, E, of any suitable form and arrangement. The arrangement which I prefer, however, is to support said stack upon a hollow or box girder, F, that 75 rests upon the walls of the kiln, as shown, as by this means I am enabled to utilize it to form the main flue D, its bottom being left open for communication with the transverse flues d, as shown in Figs. 2 and 3.

The increased height at which the heated air and afterward the spent gases and smoke are delivered by the improved construction just described will aid the draft materially, and at the same time ameliorate the inconvenience to any neighboring dwellings, by dispersing such smoke with its offensive gases and soot-flakes before they can penetrate the dwellings.

In order to control and direct the flame to 90 any part of the kiln, I arrange "dead-points" or partitions d' between the transverse flues d, and extending down some distance into the mass of bricks. These dead-points, in conjunction with gates or dampers d', that control 95 communication between the transverse flues d and the main flue D, furnish means for directing the flame to any desired portion of the kiln by opening or shutting off of the discharge from the flue d of the part of the kiln it is 100 desired to regulate.

In order to compensate for inequalities in

the "setting" of the kiln, as well as the "settling" of the mass of bricks in burning, I provide sliding plates or walls *f* at each side of the hollow girder *F*, which settle and adapt themselves to any inequality or settling, and thereby keep the flue tight against the flattening *D'* of the kiln.

It is well known that the most difficult part of a kiln to burn into hard brick is that portion directly beneath the "flattening," from four to six courses downward being usually found to be "light red" or "salmon soft bricks." To overcome this defect and burn such courses into good hard brick, I make a series of openings or flues, *g*, through the walls of the kiln, say six (more or less) courses below the flattening or top of the kiln, to act as induction-flues for the flames generated in the outside furnaces *G*.

g' are flues or passages left in the setting of the bricks in communication with the furnace-openings *g*, and extending across the kiln, as indicated in Fig. 2. These flues *g'* subserve the purpose of conducting and dispersing the flame from the furnaces *G* into direct contact with the above-mentioned courses of bricks, and thereby giving them the benefit of immediate contact with the flame which they would not receive when the firing is confined to the arches, for the reason that the gases thus formed are mostly consumed, and the greatest calorific force exerted before they reach the uppermost courses of bricks.

In carrying on brick-burning with the above process, after the bricks are burned as much as is prudent by the fires in the arches, the doors of such arches are to be closed and sealed and fires started in the furnaces *G*, to complete the proper burning of the top courses of bricks, as above mentioned.

40 In the ordinary construction of kiln there would not be sufficient draft to enable the flames from the furnaces *G* to penetrate and thoroughly burn the top courses of bricks; but by means of my improved arrangement of parts—namely, dead-points *d'*, transverse flues *d*, main flue *D*, and stack *E*—a sufficient draft and control of the flame can be established to burn the uppermost courses of the brick in the kiln harder than has heretofore been attained 45 without using the "downdraft," as in burning fire-brick.

Having thus fully described my invention, what I claim, and desire to secure by Letters Patent, is—

55 1. The herein-described mode of drying bricks in a brick-kiln, the same consisting in the use of a coil of steam-heating pipe introduced into the arches formed in the mass of bricks, substantially as and for the purpose set forth.

60 2. In a brick-kiln, the combination of the heating-coils *A* with the transverse flues *d*, for the purpose set forth.

3. In a brick-kiln, the combination of the heating-coils *A* with the transverse flues *d* and main flues *D*, for the purpose set forth. 65

4. In a brick-kiln, the combination of the heating-coils *A* with the transverse flues *d*, gates or dampers *d'*, and main flue *D*, for the purpose set forth.

5. In a brick-kiln, the combination of the heating-coils *A* with the transverse flues *d*, main flue *D*, and smoke-stack *E*, for the purpose set forth. 70

6. In a brick-kiln, the combination of the heating-coils *A* with the transverse flues *d*, dead-points *d'*, and main flue *D*, for the purpose set forth. 75

7. In a brick-kiln, the combination of the heating-coils *A* with the transverse flues *d*, dead-points *d'*, main flue *D*, and smoke-stack *E*, for the purpose set forth. 80

8. In a brick-kiln, the combination of the heating-coils *A* with the transverse flues *d*, dead-points *d'*, dampers *d''*, main flue *D*, and smoke-stack *E*, for the purpose set forth. 85

9. The combination, with a brick-kiln having an open top, of a smoke-stack, *E*, substantially as and for the purpose set forth.

10. The combination, with a brick-kiln provided with a main flue, *D*, of a smoke-stack, *E*, substantially as and for the purpose set forth. 90

11. In a brick-kiln, the combination of the furnaces *G* *g*, flues *g'*, transverse flues *d*, and dead-points *d'*, for the purpose set forth. 95

12. In a brick-kiln, the combination of the furnaces *G* *g* with the flues *g'*, transverse flues *d*, and main flue *D*, for the purpose set forth.

13. In a brick-kiln, the combination of furnaces *G* *g* with dead-points *d'*, transverse flues *d*, and main flue *D*, for the purpose set forth. 100

14. In a brick-kiln, the combination of furnaces *G* *g* with the flues *g'*, transverse flues *d*, dead-points *d'*, dampers *d''*, main flue *D*, and smoke-stack *E*, for the purpose set forth. 105

15. The combination, with a brick-kiln, of a hollow girder resting upon the permanent walls of the kiln, and acting both as a support for the smoke-stack and a main flue to receive the products of combustion, &c., substantially as and for the purpose set forth. 110

16. In a brick-kiln, the combination, with the hollow girder *F*, of side plates or walls, *f*, adapted to settle and conform themselves to any inequality or settling of the kiln contents, as described, and for the purpose set forth. 115

In testimony whereof, witness my hand this 20th day of February, 1883.

THADDEUS S. SMITH.

In presence of—

C. D. GREENE, Jr.,
A. D. GREENE.
